I. A. Sheppard

Isaac Sheppard, of Philadelphia, Penn. a DES. 2099

Letters Patent No. 2099 Dated June 18-1865.

Design for a Cook's Range.

The schedule referred to in these Letters Patent and making part of the same.

Is all whom it may concern;

Be it known that Isaac Sheppard,
of Philadelphia, County of Philadelphia, State of Pennsylvania,
have invented or produced a new and original design for the
front plate of a cooking range; and I do hereby declare the accom-
panying drawing with the following explanation of the same to
form a full, clear and exact description of the said design.

The figure in the drawing represents the front
plate of a range, to which are hinged the oven doors B.B. and
the fire place door C, a cover D, being adapted to the feed open-
ing above the door C.

Round the edges of the doors B.B. and C, is a plain
moulding a, and in the centre of each door are the oblong panels,
which are arched at the upper ends, and inclose a series of diamond
shaped projections, arranged as shown in the drawing.

Round the plate A near the edge of the same
is a plain beading b, and round the edge of the plate D, is a
broader beading c.

I claim

The figures and forms, substantially as shown in and
by the accompanying drawing, the whole forming an ornamental
design for the front plate of a cooking range.

In testimony whereof I have signed my name
to this specification in the presence of two subscribing witnesses.

Witnesses,

Charles E. Foster,

J. J. W.
